H. ESCHERT

HOT WATER HEATING UNIT

Original Filed March 11, 1918

Inventor

HERMAN ESCHERT

By his Attorney

Joseph F. O'Brien

UNITED STATES PATENT OFFICE.

HERMAN ESCHERT, OF LONG ISLAND CITY, NEW YORK.

HOT-WATER HEATING UNIT.

Application filed March 11, 1918, Serial No. 221,660. Renewed May 10, 1922. Serial No. 559,896.

To all whom it may concern:

Be it known that I, HERMAN ESCHERT, a citizen of the United States, and resident of the borough of Queens, city of New York, in the county of Queens and State of New York, have invented certain new and useful Hot-Water Heating Units, of which the following is a specification.

This invention relates to improvements in hot-water heating apparatus for apartments, rooms and the like, and more particularly to that type of such apparatus in which each radiator unit has self-contained means for supplying water and burning fuel, and means for circulating the water.

The primary object of my invention is to produce a construction of hot-water heating-unit which will provide means for causing an efficient, effective and uniform circulation of hot-water throughout the area of the entire unit, and will thus produce both quick-acting and uniform water-heating and radiation.

Another object of my invention is to produce a unit which will not only be inexpensive in construction but will provide expansion and filling means extending transversely across the circulating tubes in a substantially horizontal plane along the top of the unit, whereby compactness of construction is procured.

Still another object of my invention is to provide in such a hot-water heating-unit, a gauging device for determining when the water supply should be replenished.

In the accompanying drawings, in which similar reference characters designate corresponding parts throughout the several views,

Fig. 1 is a vertical section through the longitudinal axis of a radiator unit embodying my invention; and

Fig. 2 is an end elevation of the unit shown in Fig. 1.

Referring now to these drawings, 1 indicates a radiator unit comprising a series of vertically-disposed tubes, pipes or radiator sections which are interconnected at their upper and lower ends. Preferably the tubes 2 communicate at their lower ends with a boiling or heating chamber 3 and the adjacent walls of the tubes 2 diverge outwardly at their bottom portions to form wedge-shaped terminals 2^a within the cham-

ber 3, so as to present as slight resistance as possible to the circulation or passage of the water upwardly within the tubes 2. The chamber 3 as shown is frustro-conical in cross-section, having a substantially flat bottom 3^a and sides inwardly converging therefrom which merge or connect with the straight vertical edges of the tubes 2. At their upper ends, said interconnected tubes, as illustrated, communicate with a connecting or filling chamber 4.

A return 5 has a connection with said interconnected radiator tubes at one side of the upper end thereof, is disposed to extend transversely of said series of tubes and has a connection with the lower end of said tubes at the side opposite to the said upper connection. As shown in the drawing, this return pipe 5 has, at its upper end, a return or U-connection 5^a communicating with one end of the connecting chamber 4, from which connection the said pipe traverses the rear side of the radiator unit diagonally and has at its lower end another return or U-connection 5^b which extends below the bottom plate 3^a of the boiling chamber and connects vertically therewith at the side of the radiator unit opposite to the first-mentioned connection.

The radiator unit may be heated by any suitable fuel, the heat being applied however at the bottom of the boiler and below the radiator tubes 2. As illustrated gas burners 6, 6^a, which may be of any suitable type, are supplied by a supply pipe 7 supported on brackets 8, 8^a suspended from the bottom plate.

The unit is filled with water through a pipe 9 which is disposed transversely of the said tubes in substantially a horizontal plane along the top of the unit, and has at its free end a filling cup 10 which opens upwardly to the air. The pipe 9 is, as shown, supported by brackets 9^a, 9^b in a sufficiently inclined position to furnish sufficient pitch to cause the water to flow readily through the same into the radiator unit, but to hug the top of the radiator as closely as possible so as to be out of the way.

The pipe 9 is of sufficient diameter to permit the water in the unit to expand within the same, when heated, without overflow.

A transparent gauge 11 is also preferably

provided intermediate the ends of the pipe 9 for the purpose of indicating when the water requires replenishment.

The operation of the device is as follows:

5 The unit is filled with water through the cup 10 and pipe 9 till it shows in the indicating gauge 11 and the gas is lighter. The water within the boiling chamber 3 is thus heated and within an exceptionally 10 short period of time, complete circulation begins. The hot water rising through the tubes creates a suction through the vertical U-connection below the boiler plate and simultaneously forces the water in the boiling compartment upwardly through the tubes 2 into the connecting chamber and thence through the upper end of the return pipe and down through the same to the said vertical connection. It will be seen that the 15 disposition of the pipe 5 diagonally across the tubes 2 will, in view of the application of the heat below the boiling chamber plate 3^a, cause a uniform circulation throughout 20 of the area of the tubes.

25 Furthermore, when the water is heated, it will have sufficient space to expand within the pipe 9, and in the normal operation of the device, the gauge 11 should always be full or partially filled with water.

30 Having described my invention, I claim:
1. A radiator unit, embodying, in combination, a series of vertically-disposed radiator tubes, a boiling-chamber connected with each of said tubes at the bottom thereof, a connecting-chamber communicating with each of the said tubes at the top, a return-pipe having a connection with said connecting-chamber at one end, extending diagonally across the said tubes and having 35 a connection with the boiling-chamber at the end of the unit opposite to the first-mentioned connection; means for heating water in the unit, and means for filling the unit with water and providing space for the 40 expansion thereof under heat.

45 2. A radiator unit, embodying, in combination, a series of vertically-disposed tubes, a boiling-chamber connected with each of said tubes at the bottom thereof, a connecting-chamber communicating with each of said tubes at the top, a return pipe having a connection with said connecting chamber at one end, extending diagonally

55 across the said tubes and having a vertically-disposed connection with the bottom-plate of said boiling chamber at the end of the unit opposite to the first-mentioned connection; means for heating water in said boiling chamber, and means for filling the 60 unit with water and providing space for the expansion of the water under heat.

65 3. A radiator unit, embodying, in combination, a series of vertically-disposed radiator tubes, a boiling-chamber connected with each of said tubes at the bottom thereof, a connecting chamber communicating with each of the said tubes at the top, a return pipe having a connection with said connecting chamber at one end of the unit, 70 extending diagonally across the said tubes and having a connection with the boiling chamber at the opposite end of the unit; wedge-shaped terminals between said vertically-disposed radiator tubes within the boiling-chamber; means mounted upon the 75 unit for heating water within said boiling chamber, and means for filling the unit with water and providing space for the expansion thereof under heat.

80 4. A hot-water heating unit, embodying, in combination, a plurality of vertically-disposed tubes, a horizontally-disposed boiling chamber connected with the bottom of said tubes, another horizontally-disposed chamber connected with the top of said tubes; means for applying heat to the bottom of said boiling chamber for heating water therein; means for filling the unit with water and providing space for the expansion of the water under heat; means for 85 making a water-circulating connection with said top chamber, a return pipe and means extending below the bottom of said boiling chamber and connected to said return pipe for causing water from said return pipe to 90 be fed in an upward direction into said boiling chamber.

95 Signed at the borough of Manhattan, city of New York, in the county of New York and State of New York, this 8th day of March, A. D., 1918.

HERMAN ESCHERT.
